FUEL CONTROL VALVE

Floyd J. Bydalek and Gerald E. Dietz, Milwaukee, and Russell B. Matthews, Wauwatosa, Wis., assignors, by mesne assignments, to Penn Controls, Inc., Goshen, Ind., a corporation of Indiana

Filed Dec. 7, 1959, Ser. No. 857,720

11 Claims. (Cl. 137—624.11)

This invention relates to improvements in fuel control valves and more particularly to timer controlled valves for gas burning incinerators or the like.

In the operation of any gaseous fuel burning incinerator there is a minimum period during which the refuse should be exposed to the burning gas in order to incinerate a given load without the generation of objectionable amounts of smoke and odor. Even though the user is adequately instructed as to the minimum time setting recommended by the manufacturer for a given incinerator, such instructions are often deliberately disregarded in order to economize on fuel, with the result that a smoke and odor nuisance is created for which users sometimes wrongfully blame the manufacturer.

It is a general object of the present invention to provide an improved fuel control valve for gas burning incinerators or the like which insures complete combustion of the burnable refuse placed in the associated incinerator, without the generation of objectionable amounts of smoke and odor.

Another object of the invention is to provide an improved fuel control valve having a predetermined minimum time cycle of operation during which gas is permitted to flow therethrough to the associated burner.

A more specific object of the invention is to provide an improved timer controlled fuel control valve which cannot be set to open position for retention therein by the timing mechanism unless said timing mechanism is set to or beyond a predetermined minimum setting, there being means for preventing intentional turndown of the timing mechanism to less than said predetermined minimum setting.

Other and further objects and advantages of the invention will become apparent as the description proceeds, reference being had to the drawings accompanying and forming a part of this specification in which:

FIGURE 1 is a vertical sectional view of one form of the improved fuel control valve, the latter being shown in closed or "off" position;

FIGURE 2 is a view similar to FIGURE 1 showing the knob and associated mechanism depressed to effect opening of the valve prior to rotation of the knob effecting setting of the timing mechanism;

FIGURE 3 is a plan view of the dial and knob of the timing mechanism showing the knob in "off" position;

FIGURE 4 is a view similar to FIGURE 3 showing the knob at the predetermined minimum setting which in the illustrated device is one hour;

FIGURE 5 is a fragmentary sectional plan view taken approximately along the line V—V of FIGURE 1; and

FIGURE 6 is a fragmentary sectional plan view taken approximately along the line VI—VI of FIGURE 1.

Referring more particularly to FIGURES 1 and 2 of the drawings, the illustrated fuel control valve assembly comprises a lower body part 10 and a complementary upper body part 11 held in assembled relation, as by screws 12. The body part 10 is provided with an inlet fuel passage 13 threaded to receive a fuel supply conduit 14, and a fuel discharge passage 15 threaded to receive a conduit 16 for connection to the burner the fuel supply to which is to be controlled. The inlet and discharge passages 13 and 15, respectively, are separated by a partition 17 formed with an opening 18 surrounded by a flat

2

annular valve seat 19 (FIGURE 2). The partition 17 defines a cylindrical chamber 20, and the body part 10 is formed with a threaded opening coaxial with said chamber for receipt of a plug 21 provided with a guiding pin 22. A valve member 23 is positioned within the chamber 20 for cooperation with the valve seat 19 and is provided with a tubular guide sleeve portion 24 surrounding the guide pin 22 as shown. A helical compression spring 25 is interposed between the valve member 23 and the plug 21 and surrounds the guide pin 22 and guide sleeve portion 24, biasing the valve member 23 toward the seat 19.

The lower body part 10 is formed with an opening 26 in its upper surface coaxial with the opening 18 and communicating with the latter as well as with the outlet passage 15 as shown. The opening 26 is closed by the upper body part 11 through the intermediary of a gasket 27. The upper body part 11 is formed with a transverse partition 28 forming the bottom wall of an upper cup-shaped portion and the top wall of a downwardly facing recess 29 in registration with the opening 26 of body part 10. The partition 28 is formed with an upwardly projecting axial boss 30 which is axially bored to receive a shaft 31, said boss being formed at its upper end with a coaxial annular groove 32 for receiving a resilient O ring seal 33, the latter being retained in place by a suitable retaining washer 34 staked within a suitable coaxial recess formed in the upper end of the boss 30. The shaft 31 is movable axially as well as rotatably, and when depressed, engages 30 the valve member 23, moving the same to open position as shown in FIGURE 2.

The shaft 31 extends upwardly through a timing mechanism shown diagrammatically at 35, and is operatively associated therewith as will hereinafter appear. The timing mechanism 35 is disposed within and affixed to a cup-shaped housing member 36 telescoped within the cup-shaped upper end of the upper body part 11 as shown. A pin 37 is fixed to and depends from the casing member 36 and is axially slidably disposed within a bore 38 formed in the body part 11. The coaction of the pin 37 with bore 38 permits axial movement of the casing member 36 with the timer 35 and shaft 31, but prevents rotative movement of said casing member and timer. Telescoped over the upper end of the casing member 36 is an inverted cup-shaped casing member 39 having an enlarged diameter lower end or skirt portion 40. As shown in FIGURE 3 casing members 36 and 39 are formed with cooperating vertical indentations 41 and 42 preventing relative rotation therebetween. A helical compression spring 43 surrounds the boss 30 and is interposed between the partition 28 and the bottom wall of the casing member 36, said spring biasing the casing members 36 and 39, as well as the timer mechanism 35 and shaft 31, upwardly toward the position shown in FIGURE 1.

55 The upper casing member 39 is formed in its upper wall with a central aperture having fixed therein a flanged bearing member 44. A sleeve 45 is telescoped over the upper end of the shaft 31 and is pinned thereto by an elongated diametrically extending pin 46 shown most clearly in FIGURE 5, said pin being pressed into registering diametrical openings in the sleeve 45 and shaft 31. Relatively rotatably mounted on the sleeve 45 is a cylindrical fitting 47 having an enlarged diameter lower end portion penetrated by an axial bore 48. The fitting 47 has a reduced diameter intermediate portion 49 journaled in the bearing 44 and terminates in an upwardly extending coaxial squared shaft portion 50. The terminal portion 50 carries a knob 51, and an annular dust seal 52, for example of foamed plastic, surrounds the portion 49 of the fitting 47 between the knob 51 and the bearing 44 as shown. Because of the squared configuration of the por-

tion 50 of the fitting 47, rotation of the knob 51 effects corresponding rotation of the fitting 47.

As shown most clearly in FIGURE 5, the lower portion of the fitting 47 is formed with a cutaway sector 53 through which the pin 46 projects. In the illustrated form of the invention the sector 53 is approximately (90°) ninety degrees in extent, the size of the sector 53 depending upon the minimum time setting desired for the device. As shown in FIGURES 1, 2 and 5, the fitting 47 carries a radially projecting pin 54, and the outer end of the pin 46 carries a retainer sleeve 55, there being a helical tension spring 56 connected at one end to said retainer sleeve and at the other end to the pin 54. As shown in FIGURE 5 the spring 56 biases the fitting 47, and thereby the knob 51, in a clockwise direction with respect to the shaft 31 to maintain the relationship of said fitting and shaft shown in FIGURE 5.

As shown in FIGURES 3 and 4, the upper wall of the casing member 39 carries a dial plate 57 indicating the initial or "off" position of the knob 51 and bearing time setting indicia which in the illustrated embodiment indicates timer settings up to four hours. Means is provided for preventing counterclockwise rotation of the knob 51 beyond its initial or "off" position, said means comprising a pin 58 pressed into suitable registering openings in the bearing 44 and the upper wall of the casing member 39 and depending therefrom, said pin cooperating with a pin 59 fixed to and projecting radially from the fitting 47 as shown.

As shown in FIGURES 1, 2 and 6, a circular control disc 60 is coaxially disposed within the recess 29 and is formed with a central hub portion 61 extending above said disc and a hub portion 62 depending therefrom. The shaft 31 is formed with a reduced diameter lower end portion forming a shoulder 63, the hubs 61 and 62 being axially bored to receive the lower end portion of said shaft. An E-ring 64 is snapped into a suitable annular groove formed in the shaft 31, said ring engaging the hub 62 and retaining the hub 61 in engagement with the shoulder 63 to prevent substantial axial movement of the disc 60 with respect to the shaft 31.

As shown most clearly in FIGURE 6, the control disc 60 is formed with a radial slot or escapement portion 65. A pin 66 is pressed into a suitable aperture in the partition 28 of body part 11 and depends from said partition, said pin being accommodated within the slot or escapement portion 65 of the disc 60 when the parts are in the "off" position shown in FIGURE 1. The hub portion 62 of the disc 60 is formed with a cutaway sector 67, and a pin 68 is fixed to and projects from the shaft 31 through said cutaway portion as shown. Sector 67 is preferably of about the same angular extent as the cutaway sector 53 in the fitting 47, said cutaway sectors and the cooperating radially extending pins respectively affording lost-motion connections between the shaft 31 and knob 51 and said shaft and the control disc 60. To prevent rotation of the disc 60 except by engagement of the pin 68 with one or the other end walls 67a and 67b of the cutaway segment 67, a leaf spring 69 is disposed in frictional engagement with the periphery of the control disc 60, said leaf spring being carried by a pin 70 pressed into a suitable aperture in the partition 28 and depending therefrom.

To place the control device into operation, the knob 51 is first pressed downwardly to thereby move the shaft 31 and casing members 36 and 39, together with the mechanism therein, downwardly against the bias of the spring 43. This downward movement of the shaft 31 effects downward opening movement of the valve member 23 against the bias of the spring 25, and said downward movement also moves the control disc 60 downwardly below the lower end of the pin 66 as shown in FIGURE 2. With the parts thus depressed, the knob 51 is rotated clockwise to any desired setting above the minimum time setting which is indicated as one hour for the illustrated device. Such clockwise knob rotation effects immediate

rotation of the shaft 31 therewith in a clockwise direction, and such shaft rotation winds up the timer mechanism 35. As the shaft 31 rotates clockwise, the pin 68 swings in a clockwise direction in the cutaway sector 67 of hub 62, and just before the knob 51 reaches the predetermined minimum time setting, the pin 68 moves into abutment with the cutaway sector end wall 67a, so that further clockwise rotation of the shaft 31 with the knob 51 causes clockwise movement of the control disc 60 therewith and movement of the escapement or cutaway portion 65 out of registration with the depending pin 66. Thus no clockwise rotation will be imparted to the disc 60 in response to clockwise rotation of the knob 51 until said knob has been moved beyond the predetermined minimum setting.

Upon release of the knob 51, the parts remain in the depressed position due to the fact that the escapement portion 65 of the control disc 60 has been rotated out of registration with the depending pin 66. Immediately upon release of the knob 51, the timer mechanism 35 begins to return the shaft 31 in a counterclockwise direction at a timed rate. It will be observed, however, that no counterclockwise rotation is imparted to the control disc 60 until the pin 68 has been rotated from its position in contact with the end wall 67a of sector 67 into engagement with the opposite end wall 67b of said sector. Since the time required for movement of the pin 68 from engagement with one end wall to the other of the sector 67 is the predetermined minimum "time on" period for the device, it will be observed that no counterclockwise rotation of the control disc 60 can be effected by counterclockwise rotation of the shaft 31 until the predetermined minimum "time on" period has elapsed.

The lost-motion connection between the fitting 47 and pin 46 provided by the cutaway sector 53 prevents counterclockwise rotation of the shaft 31 by manual actuation of the knob 51 until there has been counterclockwise rotation of the knob 51 sufficient to bring the end wall 53b of cutaway sector 53 into engagement with the pin 46. However, since the knob 51 is prevented by pins 58 and 59 from being rotated in a counterclockwise direction beyond its initial or "off" position, the shaft 31 cannot be rotated manually in a counterclockwise direction to a position corresponding to less than the predetermined minimum "time on" setting. The spring 56 functions to cause the knob 51 to maintain the aforementioned predetermined relationship with the shaft 31, so that said knob rotates with said shaft in a counterclockwise direction with the passage of time and indicates on the dial 57 the length of time the device will subsequently remain on, i.e., the valve member 23 will be held open. As the shaft 31 and knob 51 approach their initial positions of rotation, the control disc 60 likewise approaches its initial position of rotation, and as the escapement portion 65 moves into registration with the pin 66 the spring 43 biases the depressed assembly upwardly, and the spring 25 biases the valve 23 to closed position in which it remains until the knob 51 is reset to initiate another operative cycle.

It is apparent that the improved device cannot be set into operation unless the knob 51 is rotated at least to the predetermined minimum "time on" setting. It is also apparent that the improved device has embodied therein non-frustratable means for preventing turndown of the device, once set to open position, to a setting less than the predetermined minimum "time on" setting prescribed by the manufacturer.

Having described the invention as embodied in one specific fuel control valve structure and organization, it is to be expressly understood that the illustrated form of the invention was selected to facilitate the disclosure and is not intended to impose any unnecessary limitations on the claims or to confine the invention to a particular use. Various changes and modifications may be made in the disclosed embodiment to meet the requirements of practice, without in any manner departing from the spirit of

the invention, and all of such changes are contemplated as may come within the scope of the appended claims.

What is claimed as the invention is:

1. In combination, a manually rotatable knob having an initial position and rotatable therefrom in one direction through a predetermined angle, a shaft rotatable from an initial position through said predetermined angle, a first lost-motion connection between said knob and shaft operative upon rotation of said knob in one direction to correspondingly rotate said shaft, the lost motion of said connection preventing subsequent reverse actuation of said shaft by reverse rotation of said knob until said knob has been rotated through a predetermined minimum angle in said reverse direction, a control member rotatable from an initial position through a predetermined angle, and a second lost-motion connection between said shaft and said control member operable only after rotation of said shaft through a predetermined minimum angle from its initial position to rotate said control member therewith from its initial position.

2. In combination, a manually rotatable knob having an initial position and rotatable therefrom in one direction through a predetermined angle, means preventing rotation of said knob in the opposite direction from said initial position, a shaft rotatable from an initial position through said predetermined angle, a first lost-motion connection between said knob and shaft operative upon rotation of said knob in one direction to correspondingly rotate said shaft, the lost motion of said connection preventing subsequent reverse actuation of said shaft by reverse rotation of said knob until said knob has been rotated through a predetermined minimum angle in said reverse direction, a control member rotatable from an initial position through a predetermined angle, and a second lost-motion connection between said shaft and said control member operable only after rotation of said shaft through a predetermined minimum angle from its initial position to rotate said control member therewith from its initial position.

3. In combination, a manually rotatable knob having an initial position and rotatable therefrom in one direction through a predetermined angle, a shaft rotatable from an initial position through said predetermined angle, a spring loaded first lost-motion connection between said knob and shaft operative upon rotation of said knob in one direction to correspondingly rotate said shaft, the lost motion of said connection preventing subsequent reverse actuation of said shaft by reverse rotation of said knob until said knob has been rotated through a predetermined minimum angle in said reverse direction, a control member rotatable from an initial position through a predetermined angle, and a second lost-motion connection between said shaft and said control member operable only after rotation of said shaft through a predetermined minimum angle from its initial position to rotate said control member therewith from its initial position.

4. In combination, a manually rotatable knob having an initial position and rotatable therefrom in one direction through a predetermined angle, means preventing rotation of said knob in the opposite direction from said initial position, a shaft rotatable from an initial position through said predetermined angle, a first lost-motion connection between said knob and shaft operative upon rotation of said knob in one direction to correspondingly rotate said shaft, the lost motion of said connection preventing subsequent reverse actuation of said shaft by reverse rotation of said knob until said knob has been rotated through a predetermined minimum angle in said reverse direction, a control member rotatable from an initial position through a predetermined angle, a second lost-motion connection between said shaft and said control member operable only after rotation of said shaft through a predetermined minimum angle from its initial position to rotate said control member therewith from its initial position, and means tending to return said shaft

toward its initial position, the lost motion in said second lost-motion connection preventing reverse actuation of said control member by return movement of said shaft until said shaft has rotated through said last-mentioned minimum angle in said reverse direction.

5. In combination, a manually rotatable knob having an initial position and rotatable therefrom in one direction through a predetermined angle, means preventing rotation of said knob in the opposite direction from said initial position, an axially movable shaft rotatable from an initial position through said predetermined angle, a first lost-motion connection between said knob and shaft operative upon rotation of said knob in one direction to correspondingly rotate said shaft, the lost motion of said connection preventing subsequent reverse actuation of said shaft by reverse rotation of said knob until said knob has been rotated through a predetermined minimum angle in said reverse direction, a control member rotatable from an initial position through a predetermined angle, a second lost-motion connection between said shaft and said control member operable only after rotation of said shaft through a predetermined minimum angle from its initial position to rotate said control member therewith from its initial position, means for moving said control member from its initial position axially with said shaft, and means for preventing substantial axial movement of said control member and shaft except when said control member is in its initial position of rotation and for preventing rotation of said control member except when the latter is moved axially from its initial position a predetermined distance.

6. In combination, a manually rotatable knob having an initial position and rotatable therefrom in one direction through a predetermined angle, means preventing rotation of said knob in the opposite direction from said initial position, an axially movable shaft rotatable from an initial position through said predetermined angle, a first lost-motion connection between said knob and shaft operative upon rotation of said knob in one direction to correspondingly rotate said shaft, the lost motion of said connection preventing subsequent reverse actuation of said shaft by reverse rotation of said knob until said knob has been rotated through a predetermined minimum angle in said reverse direction, a control member rotatable from an initial position through a predetermined angle, a second lost-motion connection between said shaft and said control member operable only after rotation of said shaft through a predetermined minimum angle from its initial position to rotate said control member therewith from its initial position, means for moving said control member from its initial position axially with said shaft, means for preventing substantial axial movement of said control member and shaft except when said control member is in its initial position of rotation and for preventing rotation of said control member except when the latter is moved axially from its initial position a predetermined distance, and a flow control member operatively related to said shaft and movable from one controlling position to another with axial movement of said shaft.

7. In combination, a manually rotatable knob having an initial position and rotatable therefrom in one direction through a predetermined angle, means preventing rotation of said knob in the opposite direction from said initial position, an axially movable shaft rotatable from an initial position through said predetermined angle, a first lost-motion connection between said knob and shaft operative upon rotation of said knob in one direction to correspondingly rotate said shaft, the lost motion of said connection preventing subsequent reverse actuation of said shaft by reverse rotation of said knob until said knob has been rotated through a predetermined minimum angle in said reverse direction, rotary biasing means tending to return said shaft to its initial position of rotation when rotated therefrom in said one direction, a control member rotatable from an initial position through a predetermined angle, a second lost-motion connection between said shaft

and said control member operable only after rotation of said shaft through a predetermined minimum angle from its initial position to rotate said control member therewith from its initial position, means for moving said control member from its initial position axially with said shaft, and means for preventing substantial axial movement of said control member and shaft except when said control member is in its initial position of rotation and for preventing rotation of said control member except when the latter is moved axially from its initial position a predetermined distance, the lost motion in said second lost-motion connection preventing reverse actuation of said control member by return movement of said shaft until said shaft has rotated in said return direction through said predetermined angle of said second connection.

8. In combination, a manually rotatable knob having an initial position and rotatable therefrom in one direction through a predetermined angle, means preventing rotation of said knob in the opposite direction from said initial position, an axially movable shaft rotatable from an initial position through said predetermined angle, a first lost-motion connection between said knob and shaft operative upon rotation of said knob in one direction to correspondingly rotate said shaft, the lost motion of said connection preventing subsequent reverse actuation of said shaft by reverse rotation of said knob until said knob has been rotated through a predetermined minimum angle in said reverse direction, rotary biasing means tending to return said shaft to its initial position of rotation when rotated therefrom in said one direction, axial biasing means tending to return said shaft axially to its initial position when depressed axially therefrom, a control member rotatable from an initial position through a predetermined angle, a second lost-motion connection between said shaft and said control member operable only after rotation of said shaft through a predetermined minimum angle from its initial position to rotate said control member therewith from its initial position, means for moving said control member from its initial position axially with said shaft, means for preventing substantial axial movement of said control member and shaft except when said control member is in its initial position of rotation and for preventing rotation of said control member except when the latter is depressed axially with said shaft from its initial position a predetermined distance, the lost motion in said second lost-motion connection preventing reverse actuation of said control member by return movement of said shaft until said shaft has rotated in said return direction through said predetermined angle of said second connection, and a valve member operatively related to said shaft and movable from closed to open position by depression of said shaft axially from its initial position.

9. An incinerator control or the like having a non-frustratable predetermined minimum time operational cycle, comprising a shaft mounted for axial and rotative movement, means biasing said shaft in one axial direction toward an initial position, a valve member operatively associated with said shaft and having means biasing the same toward closed position, said valve being depressable toward open position by axial depression of said shaft against the bias of its biasing means, a control disc having an escapement portion mounted on said shaft for axial movement therewith and having a lost-motion rotary driving connection therewith, a fixedly mounted pin cooperable with said disc and disposed in the escapement portion thereof when the latter and said shaft are in their initial positions, said pin being operable to hold said disc and hence said shaft and valve in depressed position when said disc is depressed and rotated in one direction to move said escapement portion out of registry with said pin, a timer operatively associated with said

shaft and tending to effect return rotation of the latter toward its initial position at a timed rate following rotation of said shaft in said one direction, a knob having a spring loaded rotary lost-motion connection with said shaft and operable when rotated in said one direction from its initial position to rotate said shaft therewith in said one direction, said knob being movable axially with said shaft, and means for preventing reverse rotation of said knob beyond its initial position, the lost-motion connection of said shaft and control disc preventing rotary actuation of said disc in response to rotation of said knob from its initial position until said knob has been rotated beyond a predetermined minimum time setting of said timer, said last-mentioned lost-motion connection preventing reverse rotary actuation of said disc by reverse rotation of said shaft until said timer has returned said shaft and knob through the angle corresponding to said predetermined timer setting, and the lost-motion connection between said knob and shaft preventing reverse actuation of said shaft by reverse rotation of said knob until said knob has been rotated with respect to said shaft toward its initial position through the angle corresponding to said predetermined minimum timer setting.

10. In an incinerator control or the like, a knob having an initial position and being manually movable therefrom in one direction, stop means preventing movement of said knob in the reverse direction from said initial position, a movable shaft having an initial position, a first lost motion connection between said knob and shaft operative upon movement of said knob in said one direction to correspondingly move said shaft, a timer tending to return said shaft toward its initial position at a predetermined rate, the lost motion in said first connection preventing subsequent reverse actuation of said shaft by actuation of said knob in said reverse direction until said knob has been moved a predetermined minimum amount in said reverse direction, a control member movable from an initial toward a second controlling position, and a second lost-motion connection between said shaft and said control member operable only after movement of said shaft a predetermined minimum amount from its initial position to move said control member therewith from its initial position.

11. In an incinerator control or the like, a knob having an initial position and being manually rotatable therefrom in one direction, stop means preventing rotation of said knob in the reverse direction from said initial position, a rotatable shaft having an initial position, a first lost motion connection between said knob and shaft operative upon rotation of said knob in said one direction to correspondingly rotate said shaft, a timer tending to return said shaft toward its initial position at a predetermined rate, the lost motion in said first connection preventing subsequent reverse rotation of said shaft by rotation of said knob in said reverse direction until said knob has been rotated a predetermined minimum amount in said reverse direction, a control member movable from an initial toward a second controlling position, and a second lost-motion connection between said shaft and said control member operable only after rotation of said shaft a predetermined minimum amount from its initial position to move said control member therewith from its initial position.
